Southgate, Fay & Hawley

UNITED STATES PATENT OFFICE.

HARRY G. STODDARD, OF WORCESTER, MASSACHUSETTS, ASSIGNOR TO WYMAN-GORDON COMPANY, OF WORCESTER, MASSACHUSETTS, A CORPORATION OF MASSACHUSETTS.

CRANK-SHAFT INDICATING AND MARKING MACHINE.

Application filed December 28, 1926. Serial No. 157,559.

This invention, while capable of general application to machines for indicating crank shafts and similar products, is particularly designed as an improvement in the general 5 type of crank shaft indicating and marking machine shown in the prior patent to Damerell, No. 1,595,713, issued August 10, 1926.

In machines of this general type, provision is made for centering the shaft with reference to certain selected characteristics of the shaft, and for marking or drilling the center holes therein. It is also desirable to mark a definite angular point on some portion of the crank shaft, which may be used as an 10 index to position the shaft in a definite angular position in the lathe or other machine in which the shaft is to be finished, so that the crank pins may be machined as indicated and so that there will be sufficient stock available 15 for each crank pin.

In the machine shown in the prior patent, this mark for indicating angular position was made by a punch movable on a fixed path on the machine frame. This punch produced a 20 mark of very slight depth, which was frequently entirely removed from the shaft in finishing, whereas it is desirable that the indicating mark be permanently preserved for reference after the finishing of the shaft is 25 completed.

It is one object of my invention to provide 30 means for drilling a permanent mark in an angularly defined position in a crank shaft arm, which mark may be used as a guide for further machine operations. A further object is to provide means to control the actuation of the drill in definite relation to the movement of the drill toward and from the work.

In the preferred form, I design the mechanism to rotate normally at relatively slow speed which is automatically increased to high speed as the drill is advanced toward the work, and which returns to normal or slow speed as the drill is withdrawn from the work.

My invention further relates to arrangements and combinations of parts which will be hereinafter described and more particularly pointed out in the appended claims.

A preferred form of the invention is shown in the drawings in which

Fig. 1 is a partial plan view of a crank shaft indicating machine, having my improvements applied thereto;

Fig. 2 is a sectional side elevation, taken along the line 2—2 of Fig. 1;

Fig. 3 is a side elevation, partly in section, of my improved drilling mechanism, looking in the direction of the arrow 3 in Fig. 1;

Fig. 4 is a sectional plan view of the drilling mechanism;

Fig. 5 is a front elevation of the drilling mechanism, partly in section, taken substantially along the line 5—5 in Fig. 4;

Fig. 6 is a partial side elevation of the drilling mechanism, with certain parts shown in section, substantially along the line 6—6 in Fig. 7;

Fig. 7 is a transverse sectional elevation, taken along the line 7—7 in Fig. 6; and

Fig. 8 is a partial front elevation, showing the support for the marking slide.

Referring particularly to Figs. 1 and 2, I have shown my invention as applied to a 75 machine of the type disclosed in the Damerell patent above cited. The crank shaft C is loosely supported in forked guides 10, and the several crank pins thereof are simultaneously engaged by a series of centering and indicat- 80 ing members 11, 12 and 13, as shown in Fig. 2.

The members 11 are manually adjustable by a hand wheel 14 to rock the shaft C about its axis, so as to average the inaccuracies of the crank pins and to bring the shaft to an 85 indicated position where each crank pin will have sufficient stock on all sides to permit finishing thereof.

Indicating scales 15 and 16 on the slide frames 17 and 18 enable the operator to determine at a glance whether or not a particular crank pin is within the required limits for satisfactory finishing.

By the use of the hand wheel 14 the operator is usually able to find a position in which 95 the inaccuracies of the crank pins will be offset against each other, and each pin will be in a position in which it can be satisfactorily machined. It is common to provide a separate indicating device for each of the crank 100 pins #1, #2, #5 and #6 and a single indicating device for the double center crank pins #3 and #4.

The mechanism thus far described is as

shown in the Damerell patent, to which reference may be made for a more complete disclosure of the details relating thereto.

I have shown my improved drilling mechanism as applied to one of the slide frames for the indicating members. The mechanism is shown mounted upon a slide frame 18 (Figs. 3 and 4) and comprises a drill spindle 21 having one end guided in a bearing 22 on the slide frame 18, and having its opposite end supported in bearings in a sliding block 23. The intermediate portion of the spindle 21 extends freely through a spiral gear 24 but is keyed therein so that it will rotate therewith.

The block 23 (Fig. 6) has a rack 26 engaged by a pinion 27 on a rock shaft 28 (Fig. 7) mounted in bearings in the frame 20 and having an arm 29 secured to the outer end thereof. A handle or operating member 30 is loosely pivoted to swing about the axis of the rock shaft 28 and a stud 31 fixed in the arm 29 extends outward into an enlarged opening 32 (Fig. 3) in the operating member 30, thus providing a lost motion connection therewith.

A plunger 33 (Fig. 3) engages a spring 34 in a pocket 35 in the end of the frame 18 and acts to yieldingly withdraw the block 23 and spindle 21 from the work. A stop screw 37 (Fig. 4) engages an abutment 38 and may be adjusted to limit the depth of the hole which is drilled in the crankshaft.

A drill 39 is secured to the spindle 21 by any usual chuck 40 and the outer end of the drill is preferably supported by a hardened bushing 41 closely adjacent the surface of the crankshaft to be drilled.

A second spiral gear 45 (Fig. 5) meshes with the spiral gear 24 previously described. The gear 45 is mounted on a short shaft 46 extending into a rotor casing 47 and having the rotor 48 (Fig. 3) of an air motor mounted thereon. Air under pressure is supplied through a pipe 49 to a valve casing 50, in which a valve 51 is slidably mounted. A passage 52 conveys the air under pressure from the valve 51 to an inlet 53 closely adjacent the rotor 48.

The valve 51 is normally closed by a spring 54 and has a valve stem 55 extending upward and above the casing 50. A bleed opening 56 maintains a constant restricted connection between the air supply and the passage 52, even when the valve 51 is closed, and the rotor 48 is thus continuously rotated at relatively slow speed.

A valve lever 60 is pivoted at 61 on the casing 50, with its free end resting on the valve stem 55. A cam roll 62 on the lever 60 is engaged by a cam plate 63 formed on the end of the handle member 30.

When the member 30 is moved angularly to advance the drill 39 toward the work, the

first action of the lever 30 is to depress the roll 52, thus opening the valve 51 and greatly increasing the speed of the rotor 48. This action largely takes place during the lost motion movement of the lever 30 relatively to the stud 31, so that the drill is rotating at high speed before it is advanced toward the work.

Continued movement of the lever 30 maintains the high speed and advances the drill 39 until the stop 37 engages the abutment 38. As soon as pressure on the lever 30 is released, the spring 34 will return the parts to outward inoperative position, at the same time allowing the valve 51 to close and greatly reducing the speed of the rotor 48.

As the slide frame 18 moves in a fixed path toward the axis of the machine, the drill 39 always advances in a definite angular position relative to the indicating devices, and drills a hole which always has a definite angular relation to the indicated centers of the crank pins.

If this hole is thereafter rightly used to determine the proper angular position of the crankshaft in the finishing machine, the crank pins will be so disposed that sufficient stock will be provided on all sides thereof for complete finishing. If the shaft is not correctly placed in the machine, one or more crankpins may fail to finish out properly, in which event the drilled hole is available as a check, to determine whether or not the crankshaft was properly placed in the finishing machine, thus determining whether or not the defective work should be charged against the manufacturer of the forging or against the machinist who finished the shaft.

Having thus described my invention and the advantages thereof, I do not wish to be limited to the details herein disclosed otherwise than as set forth in the claims, but what I claim is:

1. In a crank shaft indicating and marking machine, means to selectively position a crank shaft in said machine, and means to drill a hole in said crank shaft while thus positioned and in a definite angular relation to the indicated crank pin centers, comprising means to advance the drill toward said shaft, and means to increase the speed of said drill prior to its advance movement.

2. In a crank shaft indicating and marking machine, means to selectively position a crank shaft in said machine, means to advance a drill along a definite predetermined line towards said crank shaft, and means to automatically increase the speed of the drill prior to the advance movement of the drill.

3. In a crank shaft indicating and marking machine, means to center and selectively position a crank shaft therein, a drilling mechanism movable along a predetermined path toward and from the centered shaft, and a single operative device effective to in-

crease the speed of the drill and to thereafter start and effect an advance of the drill toward the work.

4. In a crank shaft indicating and marking machine, a drilling mechanism comprising a drill, means to normally rotate said drill at slow speed, and a single device effective to increase the speed of said drill and to thereafter start and effect an advance of said 10 drill toward the crank shaft.

5. In a crank shaft indicating and marking machine, a drilling mechanism comprising a drill, an air motor to rotate said drill, a valve controlling said air motor, and a 15 single manually operated device effective to open said valve and to thereafter start and effect an advance of said drill toward a crank shaft selectively positioned in said machine.

6. In a crank shaft indicating and marking machine, a drilling mechanism comprising a drill, an air motor to rotate said drill, a valve controlling said air motor, a casing for said motor having a restricted but constantly open air inlet to said motor, and means to 25 open said valve and to advance said drill towards a crank shaft selectively positioned in said machine.

7. In a crank shaft indicating and marking machine, a drilling mechanism comprising a drill, an air motor to rotate said drill, a valve controlling said air motor, and a single manually operated device effective to 30 open said valve and to advance said drill toward a crank shaft selectively positioned in said machine, said operating device including a lost motion connection between said mechanism and said device, causing a delay in the advance movement of the drill

until the speed thereof has been increased.

8. In a crank shaft indicating and marking machine, means to selectively position a crank shaft in said machine, comprising a longitudinally extending bed, a crank positioning slide thereon supported for movement transversely of said bed toward and 40 from a crank of said shaft, and means to drill a hole in said crank shaft while positioned and in definite angular relation to the indicating crank pin centers, comprising a drill spindle, bearings on said slide adapted to 45 support said spindle, and actuating means for said spindle effective to automatically increase the speed of the drill prior to the advance movement of the drill, also positioned on said slide.

9. In a crank shaft indicating and marking machine, means to selectively position a crank shaft in said machine, means to advance a drill along a definite predetermined line along said crank shaft, and means to automatically increase the speed of the drill prior 50 to the advance movement of the drill, comprising a valve and a manually actuated cam effective to operate said valve.

10. In a crank shaft indicating and marking machine, a drilling mechanism comprising a drill, means including a valve to normally rotate said drill at slow speed, and cam means effective to open said valve to increase the speed of said drill at a predetermined 55 time, and said first means effective to thereafter start the advance movement of said drill toward the crank shaft.

In testimony whereof I have hereunto affixed my signature.

HARRY G. STODDARD.
